Primary Examiner—Cathy Anne MacCormac(74) *Attorney, Agent, or Firm*—Brian Beverly; Beeson Skinner Beverly, LLP(57) **CLAIM**

The ornamental design for a dog bed, as shown and described.

DESCRIPTION

FIG. 1 is a top perspective view of a dog bed showing my new design;

FIG. 2 is a top plan view thereof;

FIG. 3 is a front elevational view thereof;

FIG. 4 is a rear elevational view thereof; and,

FIG. 5 is a right side elevational view thereof, the left side being a mirror image thereof.

The zipper and handle are shown in broken lines, for illustrative purposes only, and form no part of the claimed design.

1 Claim, 4 Drawing Sheets*FIG. 2*

FIG. 5
